UNITED STATES PATENT OFFICE.

WILLIAM N. WHITELEY, OF SPRINGFIELD, OHIO.

AUTOMATIC GRAIN-BINDER.

SPECIFICATION forming part of Letters Patent No. 415,757, dated November 26, 1889.

Application filed November 3, 1886. Serial No. 217,886. (No model.)

To all whom it may concern:

Be it known that I, WILLIAM N. WHITELEY, a citizen of the United States, residing at Springfield, in the county of Clark and State 5 of Ohio, have invented certain new and useful Improvements in Automatic Grain-Binders—namely, Improved Compress and Packer Devices Therefor—of which the following is such a full, clear, and exact description as will enable any person skilled in the art to which it 10 pertains to construct and use the same, reference being had to the accompanying drawings, forming a part of this specification.

My invention relates to that class of automatic grain-binding harvesters in which the 15 cut grain is delivered to and upon the binding-deck, or to the binding-receptacle, where it is formed into a gavel by the packers and compressor, after which it is encircled by the 20 binding-cord, carried by a curved needle-arm, bound, and discharged.

My invention consists in providing an additional support for the gavel to be packed against, consisting of a lever pivoted to the 25 compressor at one end and the other end supported by a fixed pin in the binding-deck or some fixed part thereof. This lever may be pivoted upon a fixed or adjustable pivot in the compressor, the said pivot being made adjustable, (as from one hole to another in the 30 compressor,) for the purpose of lessening the space occupied by the gavel, as is necessary in binding small bundles.

My invention further consists in the parts 35 and combinations thereof, hereinafter particularly set forth and claimed.

In the drawings, Figure 1 is a cross-section of a binder embodying my invention, the needle-arm being shown below the deck and the 40 other parts in their positions at the moment a bundle has been discharged. Fig. 2 is a cross-section of the binder, showing the positions of the parts when compressing the bundle. Fig. 3 is an end elevation of a binder, showing the gearing which operates it. Fig. 4 is a perspective view of the compressor, 45 crank-lever, and their appendages. Fig. 5 is a similar view of the needle-arm, packers, and their appendages; and Fig. 6 is a partial side 50 view showing a modification of the arrangement of the needle-arm and supplementary compressor.

Similar letters refer to like parts in the several views.

A is the binding-deck; A² is the breast-plate; a is the guard; B is the knotter; B² is the tyer-wheel; b is the binder-shaft; B³ and B⁴ are the ejectors; b² is the sheaf-board; L is the trip-lever, all constructed and arranged in the usual manner. 60

The packer-shaft c is constructed as usual, being provided with the two cranks c² and c³. The rear packer C² is suspended by the crank c³ and the link d² and is constructed as usual. The front packer C is pivoted upon the crank c² and suspended by the link d, which in turn is pivoted to and suspended by a lever D, the upper end of which is pivoted upon the compressor-shaft e. The lever D is controlled and operated by the needle-arm F, to which 70 it is connected by the rod f². The compressor E, of any usual or suitable character, is fixed upon the compressor-shaft e, and its lower end is continued downward, forming the lever E², from which the rod g extends to the 75 bracket g² of the drop-leaf G, whereby the latter is operated in the usual manner. Upon the opposite end of the compressor-shaft e is fixed the usual compressor-crank e², to which is pivoted the spring compressor-rod i, pivoted at its upper end to the right-angled lever j, the latter being pivoted to the binder-frame K and operated by a cam-track formed upon the binder-wheel k, engaging the friction-roller k², pivoted upon the lever j, in the 80 85 usual manner.

Pivoted to the compressor E is the supplementary compressor H, whose inner end is provided with a lateral projection h, bent at right angles thereto, which by coming in 90 contact with the under side of the guard a prevents that end from rising out of its place, while it is supported by resting upon the boss or hub of the needle-arm F.

Upon the packer-shaft c, opposite to the 95 cranks c² and c³, is the toothed pinion m, which operates the binder-wheel k through the medium of the intermediate gears n and n² in the usual manner and as shown in Fig. 3. The toothed pinion m is loosely fitted 100 upon the packer-shaft, being temporarily attached thereto when a bundle is to be bound by means of the usual starting and stopping device, (not shown,) which is started by the

trip-lever L, upon the opposite end of the shaft of which is the crank or lever M, arranged and operating as usual.

The needle-arm F is fixed to the needle-arm shaft f, upon the opposite end of which is the crank f³, from which it is connected to the crank-wrist p on the binder-wheel k by means of the connecting-rod P in the usual manner and as shown in Fig. 3.

10 The operation of my invention is as follows, viz: The parts being in the positions shown in Fig. 1 and a bound bundle having been ejected, the rear packer C² is operating as usual. The binder now comes to rest and 15 throws the drop-leaf G, compressor E, and supplementary compressor H into the positions shown in Fig. 2. The needle-arm retiring below the binding-deck, as shown in Fig. 1, elevates the center upon which the 20 link d of the front packer C is pivoted, thereby projecting the point thereof considerably beyond the line of the needle-arm and causing it to travel in the path indicated in Fig. 1, by which it is enabled to reach farther up 25 the binding-deck than usual, and hence gather in more grain, while the rear packer C², traveling in the usual path, (within the radius of the needle-arm,) reaches farther down the binding-deck toward the compressor and takes 30 the grain from the rear packer and forces it against the compressor E and upon the supplementary compressor H until a gavel is formed. As soon as the binder is started to bind the gavel the ascent of the needle-arm 35 throws down the lever D to the position shown in Fig. 2 and brings the path of travel of the front packer C entirely within the radius of the needle-arm, where it has an opportunity of making several strokes as the needle-arm 40 advances, when the latter forces the gavel against the compressor E and supplementary compressor H, and consequently very materially assists in compacting the gavel preparatory to binding. This position of the packer 45 C is also necessary to prevent it from taking in grain while the needle-arm is elevated and forcing it against the back thereof, while when the needle-arm is below the binding-deck the packer is enabled to reach out much 50 farther, as before described. The needle-arm having now encircled the gavel with the binding-cord, the grain is compressed within the space bounded by the needle-arm F, the compressor E, the supplementary compressor H, 55 and breast-plate A², as shown in Fig. 2, thereby forming a tightly-compressed bundle of such a form as will readily expand to a round bundle after being bound and ejected. The size of the space for the compressed bundle 60 may be varied as desired by changing the pivot-bolt connecting the supplementary compressor H with the compressor E from one hole to the other in the latter. The bundle having been bound and the cord severed, the 65 compressor E and drop-leaf G drop out of the

way and the supplementary compressor H is brought to the position shown in Fig. 2, leaving a clear space for the discharge of the bundle, which is accomplished in the usual manner by the ejectors B³ and B⁴, after which the foregoing operations are repeated at the binding of each sheaf.

In the drawings I have shown my improved variable throw-packer C as a front packer only, which I deem the preferable arrangement; but it may be used as a rear packer, or both packers may be thus arranged, if desired.

The hub or boss of the needle-arm upon which the supplementary compressor rests 80 may be formed as a cam, as shown at s, Fig. 6, so that as the needle-arm advances the inner end of the supplementary compressor may be elevated, as shown by dotted lines, thus still further aiding in compacting the 85 gavel by compressing it in a vertical as well as a horizontal direction.

Having thus described the construction and use of my invention and pointed out wherein it differs from other devices now in use, and 90 without wishing to be understood as confining my claims of invention to the exact form, proportion, or arrangement of parts herein shown, so long as the principles of construction and mode of operation herein described 95 are adhered to, what I do claim, and desire to secure by Letters Patent, is—

1. In an automatic grain-binder, a supplementary compressor consisting of a lever substantially below the deck when out of action 100 pivoted at the outer end to the compressor and at its inner end provided with a projection h, extending below the guard a, to prevent said compressor from rising too high, the said supplementary compressor being 105 adapted to support the bundle from beneath and to fall out of the way with the compressor which supports it to allow the bundle to be discharged, substantially in the manner shown and described, and for the purpose of 110 compressing the bundle equally, or nearly so, on all sides.

2. In an automatic grain-binder, a supplementary compressor consisting of a lever pivoted at the outer end to the compressor and 115 resting near its opposite end upon a cam formed upon the needle-arm shaft or some fixed part thereof, in combination with said cam, the parts being so constructed and arranged as to support and compress the bundle from beneath and to fall out of the way to allow the bundle to be discharged, substantially in the manner shown and described, and for the purpose of compressing the bundle 120 equally on all sides.

WILLIAM N. WHITELEY.
